ELECTRONIC DIGITAL MULTIPLIERS

Daniel L. Curtis, Manhattan Beach, Calif., assignor, by
mesne assignments, to Litton Industries, Inc., Beverly
Hills, Calif., a corporation of Delaware

Filed June 22, 1956, Ser. No. 593,230

10 Claims. (Cl. 235—194)

This invention relates to electronic digital multipliers, and more particularly to electronic difunction multiplier systems which are operative to generate a difunction output signal train representative of the product of two quantities respectively represented by an applied analog multiplicand signal and an applied difunction multiplier signal.

As herein utilized the term difunction signal train refers to a train of periodic signals each having either a first value representative of a first number or a second value representative of a second number, and is readily distinguished from signal trains conventional in prior art digital systems in that all of the signals in the difunction signal train which have the same value represent identical numbers. For example, if it is assumed that the difunction signal train is normalized, or in other words, that the numbers represented by the signals in the train represent two numbers of equal amplitude but opposite signs such as either a plus one or a minus one, then each of the signals in the train represents either a plus one or a minus one, the average value of the signals in the train representing the quantity to which the train corresponds. Accordingly, a difunction signal train may be termed a non-numerical representation of the quantity which the train represents, since the signals are not weighted according to any number system, or in other words, have no radix as this term is customarily employed.

Difunction signal trains may take numerous forms, the most common of which are a bilevel electrical signal train in which either a high level voltage or low level voltage is presented during each signal period, a train of bipolar electrical pulses in which one pulse is presented during each signal period, or a train of unipolar pulses in which the occurrence of a pulse during a signal period represents one of the algebraic numbers representable by the signals in the train and the absence of a pulse during a signal period represents the other algebraic number which is representable. Although subsequently it will be obvious to those skilled in the art that any of these different signal types may be employed for conveying difunction intelligence information in the difunction multipliers of the invention, it will be assumed for purposes of simplicity that the applied difunction signal trains and the product-representing difunction output signal train to be hereinafter described convey intelligence by a bilevel signal train in which either a relatively high level voltage or a relatively low level voltage is presented during each signal period.

The representation of physical or mathematical quantities by difunction signal trains has been found to be extremely useful both in the solution of mathematical equations and in the field of automatic control. For example, copending U.S. patent application Serial No. 388,780, for "Electronic Digital Differential Analyzer" by Floyd G. Steele, filed October 23, 1953, illustrates the use of difunction signal trains for communicating between the integrator of a differential analyzer, while copending U.S. patent application, Serial No. 510,673, for

"Difunction Computing Elements" by Floyd G. Steele, filed May 24, 1955, illustrates structures for adding, subtracting, multiplying and dividing quantities by operating upon difunction signal trains. Although these and other circuits heretofore constructed satisfy the requirements of many systems applications, there has remained a need for a simple multiplier circuit which is capable of multiplying together the quantities represented by an analog input signal and a difunction input signal train, and which 5 may be utilized as either an input conversion device, or as a computing element within a digital computing system.

The present invention fills the foregoing void in the art by providing difunction multipliers which, according to their basic concept, include one or more gating circuits 15 which are selectively operable under the control of the voltage levels of the individual signals in a difunction multiplier signal train to either pass or reject an applied analog multiplicand signal, the filtered average of the 20 analog signal samples being a function of the product of the quantities represented by the multiplier signal train and the analog multiplicand signal. The signal passed by the gate is then applied to an analog-to-difunction converter, which may be any one of several known types to be hereinafter described, the converter functioning to 25 filter the analog signal samples and to produce a difunction output signal representative of the product of the input quantities.

More particularly, in accordance with one embodiment 30 of the invention there is disclosed a difunction multiplier which structurally includes a pair of input gating circuits both of which feed to a common analog-to-difunction converter, and which functionally is operable to produce a difunction output signal train representative of the product 35 of the quantities represented by an applied analog signal and an applied normalized difunction signal train; as previously indicated, the term normalized is used to imply that each signal in the train having one value, such as a high level voltage for example, represents a plus one, while each of the other signals in the train represents a minus one. In this embodiment of the invention the two input gates are operated conjugately under the control of the input difunction signal trains to pass either the analog signal itself to the associated converter or to pass electrical image of the analog signal to the converter; the term "analog image signal" as herein utilized 40 implies a second analog signal whose magnitude is proportional to the magnitude of the input analog signal but whose polarity is opposite to that of the input analog signal taken with respect to a predetermined reference voltage.

According to another embodiment of the invention there is disclosed a difunction multiplier which is operative to produce a difunction output train representative of the product of the quantities represented by an applied analog signal and a non-normalized difunction input signal train, as for example a train in which signals of one value represent plus one and signals of the other value represent zero. In this embodiment the multiplication is accomplished through the use of a single gate circuit and an associated analog-to-difunction converter, the gate circuit being operable in the same manner as previously described. In still another embodiment of the invention there is disclosed a multiplier which employs only a single gate circuit, which in conjunction with a variable biasing circuit and an associated difunction converter functions to multiply the quantities represented by an analog signal and a normalized difunction input train.

70 In all of the embodiments of the invention the multiplication operation is accomplished by operating upon signals which represent directly the input quantities, and

no complex cancellation networks are required to eliminate undesired components in the output signal representing the product of the multiplication operation. In addition, each of the difunction multipliers herein disclosed may be employed in conjunction with an input filter for multiplying two input quantities which are respectively represented by two input difunction signal trains, the filter being employed for converting one of the input trains to an analog signal whose magnitude corresponds to the average value of the quantity represented by the applied train; the analog signal thereby generated is then applied to the difunction multiplier wherein it is gated in accordance with the signals sequentially appearing in the other applied difunction signal train.

It is, therefore, an object of the invention to provide difunction multipliers which are operative to produce a difunction output signal train representative of the product of the quantities represented by an applied analog multiplicand signal and difunction multiplier signal train.

It is also an object of the invention to provide difunction multipliers which are operative to multiply the quantities represented by an applied difunction input signal train and an applied analog signal to produce a difunction output signal train representative of the product of the quantities.

It is a further object of the invention to provide difunction multipliers which function to produce a difunction output signal train representative of the product of the quantities represented by an applied analog signal and a difunction input signal train by gating the analog signal under the control of the signals in the input train to produce an analog product signal, and converting the product signal to the difunction output signal.

Another object of the invention is to provide difunction multipliers operative to multiply together the quantities represented by two difunction input signal trains by converting one of the trains to a corresponding analog signal, selectively gating the analog signal under the control of the sequential signals in the other difunction train to produce an analog product signal, and converting the analog product signal to a difunction output signal train representative of the product of the input quantities.

The novel features which are believed to be characteristic of the invention, both as to its organization and method of operation, together with further objects and advantages thereof, will be better understood from the following description considered in connection with the accompanying drawings in which several embodiments of the invention are illustrated by way of example. It is to be expressly understood, however, that the drawings are for the purpose of illustration and description only, and are not intended as a definition of the limits of the invention.

Fig. 1 is a block diagram of a difunction multiplier, according to the invention;

Fig. 2 is a schematic diagram of one form of electronic gate circuit which may be employed in the difunction multipliers of the invention;

Fig. 3 is a block diagram, partly in schematic form, illustrating one form of electromechanical gate circuit which may be utilized in the difunction multipliers herein disclosed; and

Figs. 4 and 5 are block diagrams of alternate forms of difunction multipliers, in accordance with the invention.

With reference now to the drawings, wherein like or corresponding parts are designated by the same reference characters throughout the several views, there is shown in Fig. 1 a difunction multiplier which is operative to produce at an output terminal 10 a difunction signal train $\mathcal{D}_{xy}$ which represents the product of the quantities represented by an applied signal E_x and an applied difunction signal train $\mathcal{D}_y$. In this particular embodiment of the invention the analog signal is actually represented by the signal E_x which is applied to an input terminal 12, and by an image signal $-E_x$ of opposite polarity but

proportional in magnitude, the image signal being applied to an input terminal 14. The applied difunction signal train $\mathcal{D}_y$, on the other hand, includes a first signal train Y composed of sequential signals each having a fixed period and either a high level value representing a first number or a low level value representing a second number, and a complementary signal train Y' composed of sequential signals consonant with the signals in train Y, the signal in train Y' having a low level value when the simultaneously appearing signal in train Y is high and a high level value when train Y presents a signal having a low level value.

As set forth briefly hereinabove, the quantity represented by difunction signal train $\mathcal{D}_y$ over any given interval corresponds to the average value of the numbers represented by the signals in the difunction train which occur during that interval. Thus if it is assumed that the difunction train is normalized, or in other words, that a high level signal in train Y represents a plus one and a low level signal represents a minus one, the quantity represented by difunction train $\mathcal{D}_y$ is given by the equation:

$$\mathcal{D}_{y_{ave}}(+1, -1) = \frac{N_1(+1) + N_2(-1)}{N_1 + N_2} = \frac{N_1 - N_2}{N_1 + N_2} \quad (1)$$

where

N_1 =number of plus one-representing signals

N_2 =number of minus one-representing signals

and

$N_1 + N_2$ =the total number of signals occurring during the interval in which the difunction train is evaluated.

On the other hand if it is assumed that a high level signal in train Y represents a plus one and a low level signal represents a zero, then the quantity represented by the difunction train is given by:

$$\mathcal{D}_{y_{ave}}(+1, 0) = \frac{N_1(+1) + N_2(0)}{N_1 + N_2} = \frac{N_1}{N_1 + N_2} \quad (2)$$

where N_1 again equals the number of plus one-representing signals and N_2 now corresponds to the number of zero-representing signals.

With reference once more to the difunction multiplier of Fig. 1, this particular embodiment of the invention includes three basic elements, namely, an analog-to-difunction converter 16 which is operative to generate at output terminal 10 a difunction signal train representative of the amplitude and polarity of an analog signal applied at an input terminal 18, and a pair of gate circuits 20 and 22 which are selectively operable under the control of the signals in difunction train $\mathcal{D}_y$ for respectively applying to terminal 18 a current signal proportional to analog signal E_x or a current signal proportional to the electrical image signal $-E_x$. The conversion of the applied voltages E_x and $-E_x$ to corresponding current signals is accomplished by a pair of resistors 24 and 26 which respectively intercouple gates 20 and 22 to the analog-to-difunction converter.

In addition to the foregoing elements the difunction multiplier of Fig. 1 also includes a timing signal source 27 which produces a train of periodically recurring clock pulse signals cp ; these signals occur at a preselected fixed frequency corresponding to the difunction signal frequency, and are employed to synchronize the operation of the multiplier by controlling the operational frequency of converter 16, and, in addition, the input instrument or mechanism, not shown, which generates difunction signal train $\mathcal{D}_y$. It will be recognized by those skilled in the computer art that timing signal source 27 may embody any of several well-known structures for generating clock pulses, such as a magnetic drum having a timing track thereon, a free running multivibrator, or a conventional stabilized sine-wave oscillator with an associated overdriven amplifier and differentiating circuit.

Analog-to-difunction converter 16 is preferably of the

general type disclosed in copending U.S. Patent application Serial No. 540,699, for "Analog-to-Difunction Converter" by Siegfried Hansen, filed October 17, 1955, now Patent No. 2,885,662, and more specifically, is preferably structurally similar to the improved converter disclosed in U.S. Patent application Serial No. 592,963, for "Apparatus for Analog-to-Difunction Conversion" filed June 21, 1956, now Patent No. 2,885,663, by the present inventor. As shown in Fig. 1 the converter includes an integrator, such as capacitor 28, for integrating the electrical signal applied to terminal 18, a sensing element 30 responsive to the magnitude of the integral signal on capacitor 28 for setting a flip-flop 32 to a plus one-representing state whenever the integral exceeds a predetermined reference level at the end of a difunction time interval is negative with respect to the reference level at the end of a period, and a standard signal source 34 which is responsive to the difunction signals generated for feeding back to the integrator capacitor through a resistor 36 a standard or unit charge to reduce the integral signal by a predetermined amount. Accordingly, the average value of the difunction signal train presented at output terminal 10 corresponds to the average rate at which the integral of the signal applied at terminal 18 is changing, and hence corresponds to the ratio of the average amplitude of the applied signal to the full scale value which the converter is capable of representing.

Consider now the structure and operation of gate circuits 20 and 22. Each of these gates is selectively operable to present either a closed circuit or an open circuit between its associated input and output terminals, and may comprise either an electronic switching mechanism or a mechanical switching mechanism. With reference to Fig. 2, for example, there is shown a bridge type gating circuit which may be utilized for electronically opening and closing a circuit between an input terminal 12 and an output terminal 38 under the control of signals applied at a pair of control terminals 40 and 42. This particular form of gate circuit includes four diodes or crystal rectifiers 44, 45, 46 and 47, which are connected as a bridge, the junction of rectifiers 44 and 46 being connected to input terminal 12 while output terminal 38 is connected to the junction of rectifiers 45 and 47. The junction of rectifiers 44 and 45, on the other hand, is coupled through a resistor 48 to one terminal B+ of a relatively high voltage, whereas the junction of rectifiers 46 and 47 is coupled to a terminal B- of a relatively low voltage through a resistor 49. In addition, the junction of rectifiers 44 and 45 is also connected to the anode of a switching rectifier 50 while the junction of rectifiers 46 and 47 is connected to the cathode of a second switching rectifier 52, the other terminals of these rectifiers being connected to control terminals 40 and 42, respectively.

The signals which are applied to control terminals 40 and 42 are determined by whether the gate is being used in Fig. 1 to gate the analog signal E_x or its electrical image signal $-E_x$, the signal trains Y and Y' being respectively applied to terminals 40 and 42 in gate 20 and being transposed in gate 22. In either instance, the application of a low level signal to terminal 40 and a high level signal to terminal 42 will render diodes 50 and 52 conductive and will thereby clamp the junction of diodes 44 and 45 at substantially the same voltage as that of the low level signal and the junction of diodes 46 and 47 at substantially the same voltage as that of the high level signal. Consequently, diodes 44 through 47 are all back biased and a very high impedance is presented at both input terminal 12 and output terminal 38.

On the other hand when relatively high and low level signals are applied respectively to control terminals 40 and 42, rectifiers 50 and 52 are back biased and the bridge rectifiers 44 through 47 are rendered conductive from the voltages at terminals B+ and B-. Accordingly the signal applied at the gate input terminal is passed to the output terminal and then on to the integrat-

ing circuit of the analog-to-difunction converter. It should be noted, of course, that the forward impedance of the bridge rectifiers is preferably very low.

Referring once more to Fig. 1, in operation gate circuit 20 passes the applied analog signal E_x whenever a difunction signal in train $\mathcal{D}_y$ represents a plus one, while gate circuit 22 functions to pass the image signal $-E_x$ whenever a minus one is represented by the applied difunction signal train. Thus the average current supplied to the integrating capacitor in the analog-to-difunction converter may be expressed as:

$$i_{ave} = i_{1ave} + i_{2ave} = \frac{E_x}{R} \frac{N_1}{N_1 + N_2} - \frac{E_x}{R} \frac{N_2}{N_1 + N_2} \quad (3)$$

15 where

R =the resistance of resistors 24 and 26

N_1 =the number of plus ones in a given interval

N_2 =the number of minus ones in a given interval

20 By combining the terms and substituting Equation 1, Equation 3 becomes:

$$i_{ave} = \frac{E_x}{R} \left[\frac{N_1 - N_2}{N_1 + N_2} \right] = \frac{1}{R} (E_x \cdot \mathcal{D}_y) \quad (4)$$

25 or in other words, is directly proportional to the product of the quantities represented by the analog signal E_x and the difunction signal train $\mathcal{D}_y$. Inasmuch as the resistance value R provides a scaling factor so that a full scale input signal will correspond to the maximum quantity representable by the difunction output signal train, it follows that the difunction output signal generated by the difunction converter will represent the product of the quantities represented by the analog signal and the input difunction signal train, and is therefore properly designated $\mathcal{D}_{xy}$.

30 35 It is to be expressly understood, of course, that the difunction multipliers of the invention may employ other forms of electronic gate circuits, and in relatively low frequency applications may also utilize electromechanical gating mechanisms. For example, there is shown in Fig.

40 45 3 an electromechanical gate which comprises a relay amplifier 54 which is selectively operable under the control of the voltage level of a signal applied at a control terminal 56 to either open or close a pair of contacts 58 which intercouple the input terminal with an associated 50 55 output terminal 38. If it is assumed that the relay amplifier closes its associated contacts in response to a high level voltage and opens them in response to a low level signal, and that a pair of these gates are to be utilized in the circuit of Fig. 1, then the signal train Y should be applied to terminal 56 of gate 20 whereas the signal train Y should be applied to the corresponding terminal of gate 22.

55 60 In the description of the invention as set forth hereinabove it has been assumed that the input difunction $\mathcal{D}_y$ was normalized, or in other words that each signal in the train represented either a plus one or a minus one. It should be emphasized, however, that the basic teachings of the invention are also applicable to difunction multipliers wherein the signals in the multiplier difunction signal train represent either a one or a zero. It will be recalled that the method of evaluating the quantity represented by this form of difunction signal train is set forth in Equation 2 hereinabove.

65 70 75 With reference now to Fig. 4 there is shown a difunction multiplier in accordance with the invention, which is operative to generate at output terminal 10 a difunction train representative of the product of the quantities represented by an analog multiplicand signal E_x and a difunction multiplier signal train $\mathcal{D}_y$ which represents intelligence in a one-zero difunction system. As shown in Fig. 4, the multiplier again includes an analog-to-difunction converter 16 and an input gate circuit 20 which is coupled thereto, each of which elements may be structurally identical with the similarly designated components of Fig. 1. For reasons which will be apparent in view

of the discussion set forth hereinbelow, the difunction multiplier of Fig. 4 requires no additional gate nor does it require the application of an electrical image of the analog signal.

Assuming now that gate 20 in Fig. 4 interconnects its input and output terminals whenever a one-representing high level signal appears in the multiplier difunction train, and presents an open circuit in response to a zero-representing low level signal in the train, it is clear that the average current supplied to the analog-to-difunction converter is given by:

$$i_{ave} = \frac{E_x}{R} \left(\frac{N_1}{N_1 + N_2} \right) \quad (5)$$

where R is again the value of resistor 24 and N_1 and N_2 respectively corresponds to the number of one and zero-representing signals received in the interval $N_1 + N_2$. Substituting Equation 2 in Equation 5 then gives:

$$i_{ave} = \frac{1}{R} (E_x \cdot \mathcal{P}_y) \quad (6)$$

Consequently the difunction output signal train $\mathcal{P}_{xy}$ from the converter again represents the product of the quantities represented by the applied analog multiplicand signal and the difunction multiplier signal.

It should be pointed out that in the difunction multipliers of Figs. 1 and 4 the difunction output signal train $\mathcal{P}_{xy}$ may present its output intelligence in either a normalized plus one-minus one difunction system or in a non-normalized one-zero difunction system, depending upon the construction of the analog-to-difunction converter. More specifically, if the converter is structurally similar to the converter shown in Fig. 2 of the previously referenced U.S. Patent application, Serial No. 540,699, or to the improved converter shown in Fig. 1 of the previously referenced U.S. Patent application Serial No. 592,963, then the output difunction conveys the product of the input quantities directly in the plus one-minus system of difunction notation. If on the other hand the analog-to-difunction converter is structurally similar to the converter shown in Fig. 6 of U.S. Patent application Serial No. 592,963, then the output difunction conveys the product of the input quantities directly in the one-zero system of difunction notation.

It should also be pointed out that the utilization of a single multiplier gate circuit, as shown in Fig. 4, is also applicable to the multiplication of difunction signals which represent their input quantities in the normalized plus one-minus one difunction system. For example, there is shown in Fig. 5 a difunction multiplier, according to the invention, which is operative to produce at output terminal 10 a difunction output signal $\mathcal{P}_{xy}$ representative of the products of the quantities represented by an analog multiplicand signal E_x , and a difunction multiplier signal train $\mathcal{P}_y$ which represents the quantity Y in the plus one-minus one system of notation.

The difunction multiplier of Fig. 5 again includes an analog-to-difunction converter 16 and input gate 20 which is coupled to the converter by a register 24, the only difference in these elements being that the resistance of resistor 24 is

$$\frac{R}{2}$$

In addition to these elements, however, the difunction multiplier of Fig. 5 also includes a biasing circuit which comprises a resistor 60 which is employed to apply to the input circuit of the converter a bias current proportional to the analog signal's electrical image signal $-E_x$, the resistance of resistor 60 being designated R or twice the value of resistor 24.

For purposes of illustration the difunction multiplier of Fig. 5 also comprises a filter circuit 62 and an inverter circuit 64, these additional elements being included in order to emphasize that the analog signal E_x and its

electrical image signal $-E_x$ may be obtained by operating upon a difunction multiplicand signal train $\mathcal{P}_x$. For example, if filter circuit 62 includes a simple R-C filter network whose time constant is relatively large compared to the period of an individual difunction signal, then the voltage across the capacitor for a given difunction input signal pattern represents the average value of the quantity represented by the input signal train; it is clear therefore, that this voltage may be applied directly to the input circuit of multiplier gate 20, and in addition may be utilized to generate the image signal $-E_x$ by merely passing the signal through inverter 64.

In operation the current supplied to the integrator circuit of the analog-to-difunction converter includes a current component i_3 from gate 20 and a bias current component i_4 which flows through resistor 60, the average value of the resultant current being given by:

$$i_{ave} = i_3 + i_4 = \frac{2}{R} E_x \left(\frac{N_1}{N_1 + N_2} \right) - \frac{E_x}{R} \quad (7)$$

which may be rewritten as:

$$i_{ave} = \frac{E_x}{R} \left(\frac{2N_1}{N_1 + N_2} - 1 \right) = \frac{E_x}{R} \left(\frac{2N_1}{N_1 + N_2} - \frac{N_1 + N_2}{N_1 + N_2} \right) \quad (8)$$

Combining terms and substituting Equation 1 then gives:

$$i_{ave} = \frac{1}{R} E_x \left(\frac{N_1 - N_2}{N_1 + N_2} \right) = \frac{1}{R} (E_x \mathcal{P}_y) \quad (9)$$

This equation will be recognized as providing the identical product shown in Equation 4 derived hereinabove for operation upon a normalized difunction multiplier signal train. Consequently, it will be recognized that the difunction output signal train $\mathcal{P}_{xy}$ presented as output terminal 10 is directly representative of the desired product.

It is to be directly understood, of course, that other modifications and alterations may be made in the difunction multipliers of the invention without departing from the spirit and scope of the invention. For example, low pass filters may be employed in the various embodiments of the invention between the multiplier gates and their associated analog-to-difunction converters for filtering or averaging the currents supplied to the converters, and thereby providing smoothing. Accordingly, the scope of the invention is to be limited only by the spirit and scope of the appended claims.

What is claimed as new is:

1. A difunction multiplier for producing a difunction output signal train representative of the product of the quantities represented by an applied analog signal and an applied input difunction signal train, said difunction trains each being composed of sequential bivalued electrical signals each having a fixed period, and having either a first value representing a first number or a second value representing a second number, the average of the numbers represented by the signals in a train corresponding to the quantity represented by the train, said multiplier comprising: at least one gate circuit having an input terminal, an output terminal and a control terminal; means for applying the analog input signal to said input terminal and the difunction input signal train to said control terminal, said gate circuit being responsive to said difunction input signal train for presenting the analog signal at said output terminal for substantially said fixed period in response to each signal in said input train having said first value; and an analog-to-difunction converter operable to produce a difunction output signal train representative of the filtered average value of analog signals applied thereto; and means for applying to said converter the signal appearing at said gate circuit output terminal.

2. A difunction multiplier for producing a difunction output signal train representative of the product of the quantities represented by an applied analog signal and an applied input difunction signal train, said difunction trains each being composed of sequential electrical sig-

nals each having a fixed period, and having either a first value representing a first number or a second value representing a second number, the average value of the numbers represented by the signals in a train corresponding to the quantity represented by the train, said multiplier comprising: an analog-to-difunction converter operable to produce an output difunction signal train whose average value represents the quantity represented by the average value of an input signal applied thereto; a gating circuit having a control terminal, an input terminal and an output terminal; means for applying the input difunction signal train to said control terminal and the analog input signal to said input terminal, said gating circuit being operable to selectively sample the analog input signal by passing to said output terminal the analog input signal in response to each signal in said difunction input signal train having said first value, whereby the signal train appearing at said output terminal represents a function of the product of the quantities represented by the applied analog input signal and the difunction input signal train; and means for applying to said analog-to-difunction converter the signal train presented at said gate circuit output terminal.

3. A difunction multiplier for operating upon an analog signal representative of a first quantity and a difunction input signal train representative of a second quantity to produce a difunction output signal train consonant with the input train and representative of the product of said first and second quantities, said difunction input signal train being composed of sequential signals occurring at a fixed preselected frequency and having either a first value representative of a first number or a second value representative of a second number, the average of the numbers represented by the signals in the train representing the second quantity, said multiplier comprising: at least one gate circuit having an output terminal and selectively operable under the control of said difunction input signal train for presenting said analog signal at said output terminal whenever a signal in said input difunction train has said first value whereby a train of pulses is produced at said output terminal whose filtered average is a function of the product of said first and second quantities; an analog-to-difunction converter operable to produce a difunction output signal train representative of the filtered average value of an analog signal applied thereto; and means for applying to said converter the signal train presented at said gate circuit output terminal.

4. The difunction multiplier defined in claim 3 wherein the first number represented by the first-valued signals in the difunction input train is one and the second number represented by the second-valued signals in the difunction input train is zero whereby the average value of the train of pulses produced at said output terminal over a given interval is

$$\frac{E_x N_1}{N_1 + N_2}$$

where

E_x = the analog input signal;

N_1 = the number of one-representing signals occurring during the given interval; and

N_2 = the number of zero-representing signals occurring during the given interval.

5. The difunction multiplier defined in claim 3 which further includes a resistor, and means for applying to said converter through said resistor an electrical image of the analog input signal, and wherein the first and second numbers respectively represented by the first and second valued signals are plus one and minus one.

6. The difunction multiplier defined in claim 3 wherein the first and second numbers respectively represented by said first and second valued signals are plus one and minus one, respectively, and which further includes a

second gate circuit having an output terminal and selectively operable under the control of said difunction input signal train for presenting the electrical image of said analog signal at its output terminal whenever a signal in said input difunction train has said second value, and means for applying to said converter the signal train presented at said output terminal of said second gate circuit.

7. A difunction multiplier for operating upon an analog signal representative of a first quantity and a difunction input signal train representative of a second quantity to produce a difunction output signal train consonant with the input train and representative of the product of said first and second quantities, said difunction input signal train and said difunction output signal train being each composed of sequential bivalued signals occurring at a fixed preselected frequency and having either a first value representative of the number one or a second value representative of the number zero, the average of the numbers represented by the signals in the train representing the second quantity, said multiplier comprising: at least one gate circuit having an output terminal and selectively operable under the control of said difunction input signal train for presenting said analog signal at said output terminal whenever a one-representing signal is received whereby a train of pulses is produced at said output terminal whose filtered average directly represents the product of said first and second quantities; an analog-to-difunction converter operable to produce a difunction output signal train representative of the filtered average value of an analog signal applied thereto; and means for applying to said converter the signal train presented at said gate circuit output terminal whereby said analog-to-difunction converter produces as its output the said difunction output signal train representative of the product of said first and second quantities.

8. A difunction multiplier for operating upon an analog input signal representative of a first quantity and a difunction input signal train representative of a second quantity to produce a difunction output signal train consonant with the input train and representative of the product of said first and second quantities, said difunction input signal train being composed of sequential bivalued signals occurring at a fixed preselected frequency and each of said sequential bivalued signals having either a first value representative of a plus one or a second value representative of a minus one, the average of the numbers represented by the signals in the train representing the second quantity, said multiplier comprising: a gate circuit having an output terminal and selectively operable under the control of said difunction input signal train for presenting said analog signal at said output terminal whenever a signal in said input difunction train has said first value; an analog-to-difunction converter operable to produce a difunction output signal train representative of the filtered average value of an analog signal applied thereto; first impedance means for applying to said converter the signal train presented at said gate circuit output terminal; second impedance means; and means for applying to said converter through said second impedance means a second analog signal whose amplitude is directly proportional to the analog signal and whose polarity is opposite to that of the analog input signal.

9. A difunction multiplier for producing a difunction output signal train representative of the product of the quantities represented by an applied analog signal and an applied input difunction signal train, said difunction trains being composed of bivalued electrical signals each bivalued signal having a fixed period, and having either a first value representing a plus one or a second value representing a minus one, the average of the numbers represented by the signals in a train corresponding to the quantity represented by the train, said multiplier comprising: an analog-to-difunction converter operable to produce an output difunction signal train whose average

value represents the quantity represented by the filtered average value of an analog signal applied thereto; first and second gate circuits each having an input terminal; means for applying the analog input signal and an electrical image thereof to said input terminals, of said first and second gates respectively, said gating circuits being conjugately operable to selectively pass the analog signal in response to each plus one-representing signal in the input train and the electrical image of the analog signal in response to each minus one-representing signal in the input train; and means for applying to said converter the signals passed by said first and second gates.

10. A difunction multiplier for operating upon an analog signal representative of a first quantity and a difunction input signal train representative of a second quantity to produce a difunction output signal train consonant with the input train and representative of the product of said first and second quantities, said difunction input signal train being composed of sequential bivalued signals occurring at a fixed preselected frequency and each bivalued signal having either a first value representative of a first number or a second value representative of a second number, the average of the numbers represented by the signals in the train representing the second quantity, said multiplier comprising: at least one gate circuit having an output terminal and selectively operable under the control of said difunction input signal train for presenting said analog signal at said output terminal whenever a signal in said input difunction train has said first value whereby a train of pulses is produced at said output terminal whose filtered average is a function of the products of said first and second quantities; an analog-to-difunction converter operable to produce a difunction output signal train representative of the filtered average

value of an analog signal applied thereto, said converter comprising an integrator for integrating signals applied to said converter to produce an integral signal, a sensing element operable to sample the integral signal at the fixed preselected frequency and to generate an output signal whenever the integral signal exceeds a predetermined reference level, means for generating a difunction output signal having said first value whenever an output signal is produced by said sensing element and a difunction output signal having second value whenever the integral signal is below said predetermined reference level when sampled, and a feedback network for feeding back to said integrator a standard unit signal to reduce the integral signal negatively with respect to said reference level in response to each difunction signal representing said first value and to reduce the integral signal positively with respect to said reference level in response to each difunction signal representing said second value; and means for applying the signals presented at said output circuit of said gate circuit to said integrator of said analog-to-difunction converter.
